in his capacity

Patentee & Co-patentee

United States Patent Office.

EDWARD DITHRIDGE, OF PITTSBURG, PENNSYLVANIA.

Design No. 2,727, dated August 6, 1867.

DESIGN FOR A REFLECTOR.

The Schedule referred to in these Letters Patent and making part of the same.

TO ALL WHOM IT MAY CONCERN:

Be it known that I, EDWARD DITHRIDGE, of the city of Pittsburg, in the county of Allegheny, and State of Pennsylvania, have originated and designed a new Design for a Reflector for illuminating purposes, of which the following is a full, clear, and exact description, reference being had to the drawing accompanying this specification, and forming part thereof, and in which—

Figure 1 is a front view of my improved reflector, and

Figure 2 is a sectional view through the line $z z$ in fig. 1.

The reflector is made of glass, and is hollow, the interior surface being lined with a deposit of silver in the usual manner. The general surface of the face of the reflector is concave, but instead of having a smooth unbroken surface, there is a series of circular depressions or concavities arranged around a central circular depression, c , the diameter of the depressions in each circle increasing toward the circumference, as shown in the drawings.

What I claim as my invention, and desire to secure by Letters Patent, is—

The design for reflector for illuminating purposes, hereinbefore set forth and shown.

In testimony whereof I, the said EDWARD DITHRIDGE, have hereunto set my hand.

Witnesses:

Jos. A. BUTLER,

W. BAKEWELL.

EDWD. DITHRIDGE.
